UNITED STATES PATENT OFFICE

JOSEPH NESTER, SR., OF EAST ST. LOUIS, ILLINOIS

DESIGN FOR A BOTTLE

Application filed January 28, 1931. Serial No. 38,462. Term of patent 14 years.

To all whom it may concern:

Be it known that I, JOSEPH NESTER, SR., a citizen of the United States of America, and residing in the city of East St. Louis, St. Clair County, State of Illinois, have invented a new, original, and ornamental Design for Bottles, of which the following is a specification, reference being had to the accompanying drawing, forming a part thereof, in which—

Fig. 1 is a front view of the article showing my new design, the rear view being the same;

Fig. 2 is a side elevation of the same; and

Fig. 3 is a horizontal cross section of the same.

I claim:

The ornamental design for a bottle as shown and described.

In testimony whereof, I have signed my name to this specification.

JOSEPH NESTER, SR.
